HOOD FOR SECURING MEANS OF MONEY BAGS OR THE LIKE

Paul F. D'Aleo, Valley Stream, N. Y.

Application March 25, 1950, Serial No. 8,763

Term of patent 14 years

(Cl. D17—3)

To all whom it may concern:

Be it known that I, Paul F. D'Aleo, a citizen of the United States, residing at Valley Stream, in the county of Nassau and State of New York, have invented a new, original, and ornamental Design for a Hood for Securing Means of Money Bags or the like, of which the following is a specification, reference being had to the accompanying drawing, forming part thereof.

In the drawing

Fig. 1 is a perspective view of a hood for securing means of money bags or the like, showing my new design;

Fig. 2 is a top plan view;

Fig. 3 is a side view;

Fig. 4 is a rear view; and

Fig. 5 is a front view.

I claim:

The ornamental design for a hood for securing means of money bags or the like, substantially as shown.

PAUL F. D'ALEO.
